UNITED STATES PATENT OFFICE

DONALD F. AINSLIE, OF BISHOP, CALIFORNIA

DRAWBAR

Application filed January 14, 1931. Serial No. 508,749.

- This invention relates to new and useful improvements in draw bars, and more particularly to a bar particularly adapted for use in connection with a tractor.
- 5 The principal object of this invention is to provide a draw bar which will be positive-acting, and which when not in use will be compact and not susceptible to the ready developments of defects.
- 10 During the course of the following specification and claims, other important objects and advantages of the invention will readily become apparent to the reader.
- In the drawings:—
- 15 Figure 1 represents a fragmentary side elevational view of a tractor with the draw bar in use therewith.
- Fig. 2 represents a longitudinal sectional view through the draw bar.
- 20 Fig. 3 represents a longitudinal sectional view through the draw bar in released position.
- Fig. 4 represents an end elevational view looking at the tractor end thereof.
- 25 Fig. 5 represents a sectional view, taken substantially on the line 5—5 of Fig. 3.
- Fig. 6 represents a sectional view taken substantially on the line 6—6 of Fig. 3.
- 30 Fig. 7 represents a fragmentary detailed sectional view through the load spring adjusting means.
- Fig. 8 represents an end view of one of the abutting collars.
- Fig. 9 represents a front elevational view 35 of the draw bar barrel.
- Fig. 10 represents another side elevational view of the draw bar barrel.
- Fig. 11 represents a perspective view of one of the levers.
- 40 Fig. 12 represents a perspective view of the removable pin.
- Referring to the drawings wherein like numerals designate like parts, it can be seen that the draw bar includes a barrel provided with a pair of diametrically opposed elongated slots 6 at its intermediate portion, and a pair of diametrically opposed and somewhat shorter slots 7 inclined toward one end of the barrel from the aforementioned slot 6 and on a plane at right angles to the slot 6.

One end of the barrel is provided with threads 8 onto which the threaded collar 9 is engageable. Rivets extend through this end portion of the barrel for securing the blocks 9'—9' within the barrel to guide the 55 pair of levers, each generally referred to by numeral 10.

Each of these levers 10 includes an elongated bar 11 having a laterally disposed head 12 at one end thereof. The opposite end of 60 the bar is bifurcated by the slot 13 to provide the legs 14 and 15, the leg 15 being substantially longer than the leg 14 and being provided with an inwardly disposed oblique foot 16.

The adjacent end of the leg 14 is beveled at its outer corner as at 17. A lug 18 projects laterally on the same side as the head 12, and is located at the point where the bifurcated portion of the bar 11 terminates at 70 its inner extent.

These bars 10 are to be assembled in overlapping relation and in opposed relation, with the openings 19 registering so that the same can be secured to the usual tailpiece 20 75 (see Fig. 1) of a tractor generally referred to by numeral 21, by a suitable securing element 22.

A slide sleeve 23 is located on the intermediate portion of the barrel 5 and is provided with a collar 24 on its outer end, the same being reduced at its inner side to provide the annular pocket 25 for receiving the lugs 18 on the levers 10. A slide collar 26 located over the portion of the barrel having the slot 7 80 therein, and this sleeve 26 is provided with the collar 27 which is adapted for abutment with the collar 25, when the draw bar is without a load.

Another collar 28 is stationarily secured to the barrel 5 by the bolts 29—29 and interposed between the collar 28 and the collar 27 is the buffer spring 30. The sleeve 26 is provided with slots registering with the slots 7 and thru the slots extends the key 31 provided with openings 32 in the ends thereof for receiving cotter pins 33 in the manner shown in Fig. 6. This key 31 is adapted for disposition thru the slots 13 of the levers 10 when the draw bar is in a position without 105

the load. In this position of the draw bar, the lugs 18 are engaging within the pockets 25 and the load spring 34 which is interposed between the adjusting nuts 35 on the threaded portion 8 of the valve, and the collar 24 is extended fully.

Fig. 3 shows the elongated bars 11 about to be released from the barrel 5. In the position shown, the lugs 18 have just disengaged from the pocket 25 of the collar 24 and the spring 34 is about to urge the collar 24 in the direction toward the collar 27. From this position, the bars 11 pull out of the barrel, thus permitting separation of the tractor 15 and trailer.

In order to permit assembly of the coupling, the bars 11 are inserted in the barrel 5 and are forced backwardly until the oblique feet 16 of the legs 15 engage the bolts 29. This results in a contraction of the legs 15 which obviously separate the legs 14 so that they ride on opposite sides of the key 31 and when the key is disposed in the position substantially shown in Fig. 2, the lugs 18 will snap into the pocket 25 of the collar 24, and thus the draw bar is firmly connected together again.

The spring 34 will exert sufficient tension against the collar 24 to always maintain the bars within the barrel until sufficient force is exerted to overcome the spring sufficiently to permit disengagement of the leg 14 from the key 31. At this point, the lugs 18 will readily ride out of the pockets 25 (see Fig. 3) and immediately, the bars will disconnect from the barrel entirely. The jamb nut 35 can be fed on the threaded portion of the barrel 5 to maintain the spring compressed against the collar 24, so that the bars can be used without the automatic control operation, and furthermore this nut 35 is employed to vary the tension of the spring 34 when the same is employed for automatic control.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

1. A draw bar comprising a barrel, a pair of rockable levers, a fixed collar on the barrel, a slideable collar on the barrel, a spring interposed between the collars, and lugs on the levers for engagement with the slideable collar.

2. A draw bar comprising a barrel, a pair of rockable levers, a fixed collar on the barrel, a slideable collar on the barrel, a spring interposed between the collars, lugs on the levers for engagement with the slideable collar, and a buffer spring, for absorbing the shock of

the collar when the same is released suddenly.

3. A draw bar comprising a barrel, a stationary collar and a slideable collar on the outside of the barrel, a pair of swingable levers projecting into the said barrel, each of said levers being provided with a lug for engagement with the said slideable collar, each of said levers being provided with a slot in the end thereof located within the barrel, and a pin 70 for disposition thru the barrel and through the slot in the levers when registering.

4. A draw bar comprising a barrel, a stationary collar and a slideable collar on the outside of the barrel, a pair of swingable levers projecting into the said barrel, each of said levers being provided with a lug for engagement with the said slideable collar, each of said levers being provided with a slot in the end thereof located within the barrel, a 80 pin for disposition through the barrel and through the slot in the levers when registering, a foot member on each of the last-mentioned ends of the levers, and a pair of transversely disposed members within the barrel 85 between which the feet are adapted to engage when the levers are retained by the key.

5. A draw bar of the character described comprising a barrel, a pair of stationary collars on the barrel, a pair of slideable collars 95 between the stationary collars in opposed relation to each other, compressible springs between the stationary collars and the corresponding slideable collars, one of the said slideable collars being provided with a recess therein, said barrel being provided with slots therein registering with the recess, and a pair of levers projecting into the said barrel, each lever being provided with a lug for disposition through a slot in the barrel and for engagement into the recess of the aforementioned slideable collar.

6. A draw bar comprising a barrel, a pair of rockable levers, a slideable collar on the barrel, said barrel being provided with slots 110 therein, projections on the levers extending through the slots for engagement with the slideable collar, an adjustable collar on the barrel, and a compressible spring interposed between the slideable collar and the said adjustable collar.

In testimony whereof I affix my signature.
DONALD F. AINSLIE.
